UNITED STATES PATENT OFFICE.

SIDNEY C. GAUNT, OF CHICAGO, ILLINOIS, ASSIGNOR TO BARNHART BROTHERS & SPINDLER, OF CHICAGO, ILLINOIS, A CORPORATION OF ILLINOIS.

DESIGN FOR A FONT OF TYPE.

No. 39,721.

Specification for Design.

Patented Dec. 22, 1908.

Application filed April 25, 1908. Serial No. 429,287. Term of patent 7 years.

To all whom it may concern:

Be it known that I, SIDNEY C. GAUNT, a citizen of the United States, residing at Chicago, in the county of Cook and State of Illinois, have invented a new, original, and ornamental Design for a Font of Type, of which the following is a specification, reference being had to the accompanying drawing, forming part thereof.

The drawing is a view of the characters of a font of type, showing my new design.

The design here presented is a solid black type, and the letters are shown as being of a broad, heavy black face, the tail pieces of the various letters being shown as coming to a round extremity, gradually tapering. Likewise such letters as f, j, J are provided with

an abrupt hook. The general sloping characteristic is present in letters such as C, G, c and similar letters whose general direction is from the upper right-hand corner to the lower right-hand corner. I also show the general sloping, square outlined, heavily faced characters, which indicate the punctuation marks as forming the harmonious design with the remaining character of the type.

I claim:

The ornamental design for a font of type, as shown and described.

SIDNEY C. GAUNT.
